CHICK FEEDER TRAY

William Van Ness, Upper Saddle River, N.J.
(11 Railroad Place, Belleville, N.J. 07109)

Filed Sept. 20, 1974, Ser. No. 507,691

Term of patent 14 years

Int. Cl. D30—03

U.S. Cl. D30—16

FIG. 1

FIG. 2

FIG. 3

FIG. 4

FIG. 5

FIG. 1 is a top plan view of a chick feeder tray showing my new design;

FIG. 2 is a side elevational view;

FIG. 3 is an end elevational view;

FIG. 4 is a bottom plan view; and

FIG. 5 is an enlarged scale cross-sectional view taken along line 5-5 of FIG. 1.

The characteristic feature of the design resides particularly in the appearance of the bottom of the tray, the bottom being dimpled on its upper surface with the bottom surface smooth.

I claim:

The ornamental design for a chick feeder tray, as shown and described.
